UNITED STATES PATENT OFFICE.

EZECHIEL WEINTRAUB, OF LYNN, MASSACHUSETTS, ASSIGNOR TO GENERAL ELECTRIC COMPANY, A CORPORATION OF NEW YORK.

VARIABLE-RESISTANCE DEVICE.

1,110,848.

Specification of Letters Patent. Patented Sept. 15, 1914.
Application filed August 18, 1911. Serial No. 644,803.

To all whom it may concern:

Be it known that I, EZECHIEL WEINTRAUB, a citizen of the United States, residing at Lynn, county of Essex, State of Massachusetts, have invented certain new and useful Improvements in Variable-Resistance Devices, of which the following is a specification.

My invention relates to variable resistance contacts, such as microphones, variable pressure regulators, or the like.

It is well known that when an electric circuit contains an imperfect carbon contact that variations of pressure on the contact produce variations in its electrical resistance. This property of carbon is utilized, for example, in telephone transmitters.

In accordance with my invention, a material containing elemental boron and a material capable of combining or alloying therewith to modify its resistance, as for example, carbon, aluminium, magnesium, and the like, is employed in place of carbon in a microphone, or similar variable contact resistance device. Preferably, I use a material containing boron and carbon.

In the accompanying drawings, Figure 1 shows diagrammatically a variable resistance contact made with a vibrating diaphragm, and Fig. 2 is a sectional view of a telephone transmitter in which the boron material may be used.

The material employed in accordance with my invention may be made by a number of methods, as disclosed in my Patent No. 1,019,393. For example, to produce a material containing boron and carbon, which I may call boro-carbon, a carbon filament may be heated in the presence of a mixture of boric chloride and hydrogen. Elemental boron is reduced and deposited on the surface of the filament. At a high temperature the carbon and boron dissolve or combine with each other and in this manner a boro-carbon containing any desired percentage of carbon may be produced, by varying the thickness of the filament or the thickness of the deposit. Elemental boron produced in accordance with the process disclosed in my Patent No. 997,879 may be mixed with carbon, or other conductive material, both the

boron and carbon being in a finely divided state. The mixture is then pressed up into coherent form either with or without a small amount of carbonaceous binder, is baked and then is fused in a high potential arc in a protective atmosphere. Various other methods are disclosed in Patent No. 1,019,393.

For the purpose of my invention, I prefer to use well fused boron associated with 5 to 60 per cent. of carbon or even more. This material is used in granular form, as plates or any form which the particular construction of the device in which it is employed may demand. I have shown diagrammatically in Fig. 1 a diaphragm 1 and a boron-containing contact 2, provided with current connections. I have shown in Fig. 2 a telephone transmitter containing granular boron material 3 as illustrative of one of the uses to which a microphonic contact may be put. Others will suggest themselves to those skilled in the art. This transmitter is of the usual construction, having a back or frame 4, a mouthpiece 5, a diaphragm 6 and 75 suitable means for making current connections as indicated and well understood by those skilled in the art of telephony.

As a resistance-varying element, boron-carbon possesses the advantage of having a higher resistance than the various forms of carbon, and its resistance may be varied through a wide range by varying the content of carbon, aluminium, etc., as the case may be. The higher specific resistance enables higher voltages to be used in the circuit containing the microphone or other variable resistance device. The boron alloys in their physical characteristics are superior also in other particulars, such as hardness, to the various forms of carbon for use in microphones and allied purposes.

What I claim as new, and desire to secure by Letters Patent of the United States, is:—

1. In a variable resistance device, the combination of a resistance-varying material comprising boron associated with carbon, current connections therefor, and means for exerting a variable pressure upon said material.
2. In a microphone, a resistance-varying element containing boron in the elemental

state, and a conductive element associated therewith.

3. In a microphone, a conductive contact material consisting of boron combined with

5 carbon.

4. In a microphone, a diaphragm, a resistance-varying material consisting of carbon and boron, and current connections

making said material part of an electric circuit.

In witness whereof, I have hereunto set my hand this sixteenth day of August, 1911

EZECHIEL WEINTRAUB.
